UNITED STATES PATENT OFFICE.

LEN GRESHAM, OF PETERSBURG, VIRGINIA, ASSIGNOR OF ONE-HALF TO EDWARD D. MACFEE, JR., OF PETERSBURG, VIRGINIA.

IGNITION ATTACHMENT FOR INTERNAL-COMBUSTION ENGINES.

1,277,913.

Specification of Letters Patent. Patented Sept. 3, 1918.

Application filed September 28, 1917. Serial No. 193,732.

To all whom it may concern:

Be it known that I, LEN GRESHAM, a citizen of the United States, residing at Petersburg, in the county of Dinwiddie and State 5 of Virginia, have invented new and useful Improvements in Ignition Attachments for Internal-Combustion Engines, of which the following is a specification.

The present invention relates to improvements in ignition attachments for internal combustion engines, and the primary objects 10 of the invention are to provide an attachment of this character which is relatively inexpensive in construction and capable of 15 being easily mounted on the engine and which will indicate with certainty the existence and the location of defective ignition and which will also improve the ignition by producing more effective sparking at the 20 spark plugs and will prevent fouling of the plugs by oil or carbon.

To these and other ends, the invention consists in certain improvements, and combinations and arrangements of parts, all as 25 will be hereinafter more fully described, the novel features being pointed out particularly in the claims at the end of the specification.

In the accompanying drawing:

30 Fig. 1 is a top plan view of an internal combustion engine equipped with an ignition attachment constructed in accordance with the present invention.

Fig. 2 represents a vertical section 35 through the attachment on the line 2—2 of Fig. 1.

Fig. 3 represents a transverse section 40 through the attachment on the line 3—3 of Fig. 2.

Similar parts are designated by the same 45 reference characters in the several views.

Ignition attachments embodying the present invention are applicable, generally, to 50 internal combustion engines which employ spark plugs for igniting the charges of explosive gas in the cylinders, it being particularly applicable to engines of this type as employed in automobiles, motor boats, and other motor vehicles. The preferred 55 embodiment of the invention is shown in the accompanying drawing and will be hereinafter described in detail, but it is to be understood that the invention is not restricted to the precise construction and arrangement shown, as equivalent constructions

and arrangements are contemplated and will be included within the scope of the claims.

In the present instance, 1 represents the upper portion of a gasoline or internal combustion engine, such as commonly employed in the propulsion of automobiles. These engines have different numbers of cylinders and the number of spark plugs used varies with the number of cylinders. The present 60 invention is applicable to engines of this class, irrespective of the number of cylinders and spark plugs that may be employed. In the present instance, the engine is shown conventionally as having a set of four spark 65 plugs 2, and the spark plugs may be of any of the types commonly used, these plugs having terminals 3 at their upper ends which are connected to one of the electrodes of the respective plugs and, ordinarily, the 70 ignition wires 4 are attached directly to the terminals 3 of the spark plugs, these ignition wires leading from a distributor which receives high tension current from a magneto 75 or from a spark coil.

The attachment embodying the present invention comprises a support or member 5 which may be conveniently formed of a strip of wood of suitable length, this member having brackets 6 on its lower side 80 which serve to fasten the attachment to the engine. Preferably, and as shown, the brackets 6 have slotted ends 7 which are adapted to be slipped under the heads 8 of the bolts which hold the head of the cylinders upon the body thereof, or these bolts 85 may be used for holding other parts to the engine, the attachment being applied by loosening such bolts, inserting the slotted ends 7 of the brackets beneath the heads of 90 the bolts, and then tightening the bolts to clamp the brackets firmly to the engine. The member 5 serves to support a set of electrodes 9 which correspond in number 95 to the number of spark plugs employed, and these electrodes are held in coöperative relation with the support or member 5 by a clamping strip 10 which overlies the electrodes and is secured in a suitable way to the top of the member 5. The electrodes 9 100 extend transversely of the members 5 and 10, and these members 5 and 10 extend longitudinally of the row of spark plugs. Preferably, the electrodes 9 are adjustable 105 individually in a direction transversely of 110

the members 5 and 10 in order to provide a spark gap 11 between the terminal of each spark plug and the adjacent end of the electrode 9. For this purpose, a pair of screws 5 12 extends through the upper member 10 at opposite sides of each electrode and these screws are secured in the lower member 5. While these screws are loosened, the electrodes may be adjusted relatively to the 10 members 5 and 10 in order to adjust the length of the spark gaps 11, and when the screws 12 are tightened the electrodes are firmly and immovably secured or clamped between the supporting members 5 and 10. 15 In order to guide the electrodes relatively to the member 5 and thereby maintain the electrodes in alinement with the respective spark plugs, a groove 13 is preferably formed in the upper face of the member 5 20 in which the electrode is slidable, the electrode, however, being of a greater thickness than the depth of the groove in order that the upper member 10 may exert a clamping action upon the electrode. The outer end of 25 each electrode is provided with a terminal 14 and, in using the attachment, the ignition wires 4 are connected to these terminals 14 of the electrodes instead of being attached directly to the terminals of the spark 30 plugs. Ordinarily, the same ignition wires which usually extend directly to the spark plugs may be used without alteration, it being necessary in applying the attachment to merely transfer these ignition wires from 35 the terminals on the spark plugs to the terminals 14 on the electrodes.

In operating an internal combustion engine equipped with an ignition attachment embodying the present invention, the current for producing the sparks at the spark 40 plugs is conducted to the plugs through the medium of the electrodes 9 which are interposed between the plugs and the ignition wires, the current being compelled to jump 45 the gaps 11 between the electrodes and the terminals of the plugs in order to complete the circuit. The sparks passing the gaps 11 will be visible, and should defective ignition occur the absence of a spark at any one of 50 these gaps at the moment it should pass will indicate that the particular spark plug to which the gap corresponds does not receive the necessary current, and this will enable the operator or attendant to remedy the 55 defect. I have also discovered that, by operating an internal combustion engine equipped with an ignition attachment of this character, fouling of the spark plugs by

oil or carbon is practically eliminated, as the jumping of the spark through the exterior gaps produces a more intense spark between the electrodes of the spark plugs. This intensified spark also produces more perfect combustion in the cylinders and results in greater power and smoother operation of the engine. 65

I claim as my invention:—

1. An attachment for the ignition systems of internal combustion engines comprising a support carrying electrodes having terminals for connection to the ignition wires spaced from the respective spark plugs to form spark gaps between them and the spark plugs. 70

2. An attachment for the ignition systems of internal combustion engines comprising a support having means for mounting it in fixed relation to the engine and longitudinally of the row of spark plugs thereof, and a set of electrodes carried by and projecting laterally from the support and spaced from the respective plugs to form spark gaps, the electrodes having terminals thereon for the attachment of the ignition wires. 75

3. An attachment for the ignition systems of internal combustion engines comprising a support having means for mounting it in fixed relation to the engine and longitudinally of the row of spark plugs thereof, and a set of electrodes carried by the support 80 and spaced from the respective plugs to form spark gaps, the electrodes being adapted for attachment to the ignition wires and being individually adjustable transversely of the support to vary the spark 85 gaps between them and the respective plugs. 90

4. An attachment for the ignition systems of internal combustion engines comprising a support adapted to be fixed to the engine in parallelism with the row of spark plugs 10 thereof and having guides thereon, electrodes slidable in said guides in a direction toward and from the respective spark plugs to form adjustable spark gaps between them and the plugs, and a clamping 10 member overlying said support and operative to hold the electrodes in adjusted position. 100

In testimony whereof I have hereunto set my hand in presence of two subscribing witnesses. 11

LEN GRESHAM.
